CLAIM

The ornamental design for a structural member, as shown and described.

DESCRIPTION

FIG. 1 is a left hand side perspective view of a structural member of the right hand side perspective view being a mirror image thereof;

FIG. 2 is a front view of the member of FIG. 1, the rear view being the same as the front view;

FIG. 3 is a top plan view of the member of FIG. 1, the bottom plan view being the same as the top plan view; and, FIG. 4 is a right end view of the member of FIG. 1, the left end view being the same as the right end view.

The structural member is been broken in the center to indicate indeterminate length.
